DESIGN FOR A CHAIR

John H. Page, Muskegon, Mich., assignor to The Shaw-Walker Company, Muskegon, Mich., a corporation of Michigan

Application June 19, 1939, Serial No. 85,570

Term of patent 7 years

To all whom it may concern:

Be it known that I, John H. Page, a citizen of the United States of America, residing at Muskegon, in the county of Muskegon and State of Michigan, have invented a new, original, and ornamental Design for a Chair, of which the following is a specification, reference being had to the accompanying drawing, forming a part thereof.

Figure 1 is a perspective view of a chair showing my new design; and Figure 2 is a side elevational view thereof.

I claim:

The ornamental design for a chair, substantially as shown.

JOHN H. PAGE.
